US00D793262S

(12) **United States Design Patent** (10) Patent No.: **US D793,262 S**
(45) Date of Patent: **** Aug. 1, 2017**

(54) **WIRELESS SENSORS**

(71) Applicant: **Tyco Fire & Security GmbH**,
Neuhausen am Rheinfall (CH)

(72) Inventors: **Zohar Geskin Zinovi**, Ramat Gan (IL);
Vitaly Roytenburd, Rishon Le Zion
(IL); **Yigal Brodetsky**, Rishon Le Zion
(IL)

(73) Assignee: **Tyco Fire & Security GmbH**,
Neuhausen am Rheinfall (CH)

(**) Term: **14 Years**

(21) Appl. No.: **29/514,636**

(22) Filed: **Jan. 14, 2015**

(51) LOC (10) Cl. **10-05**

(52) U.S. Cl.
USPC **D10/104.1**

(58) **Field of Classification Search**

USPC D10/104.1, 106.1; D26/67
CPC G08B 13/22; G08B 13/24; G08B 13/26
See application file for complete search history.

(57) **CLAIM**

Ornamental designs for wireless sensors, as shown and described.

DESCRIPTION

FIG. 1 is a top perspective view of a wireless sensor showing our new design;

FIG. 2 is a bottom perspective view thereof;

FIG. 3 is a top view thereof;

FIG. 4 is a bottom view thereof;

FIG. 5 is a front view thereof;

FIG. 6 is a rear view thereof;

FIG. 7 is a left view thereof; and,

FIG. 8 is a right view thereof.

The broken lines depict unclaimed environmental subject matter.

1 Claim, 7 Drawing Sheets

Top perspective view

FIG. 1

Top perspective view

FIG. 2

Bottom perspective view

FIG. 3

Top view

FIG. 4

Bottom view

FIG. 5

Front view

FIG. 6

Rear view

FIG. 7

Left view

FIG. 8

Right view
